UNITED STATES PATENT OFFICE

1,946,123

RAIL LUBRICATOR

Harry B. Bates, Chicago, Ill., assignor to
Maintenance Equipment Company, Chicago,
Ill., a corporation of Illinois

Application August 23, 1930. Serial No. 477,266

15 Claims. (Cl. 184—3)

My invention relates to lubricating devices and more particularly to a device for lubricating rails and car wheel flanges of railway systems.

Due to lateral thrust by car wheel flanges as a result of centrifugal force generated in traversing curves, the rails are particularly susceptible to wear at the curves and there is also a considerable wear on the wheel flanges. The thrust comes on the innerside of the rail face where the car wheel flange contacts and in practice it has been found necessary to frequently replace the worn rails to avoid derailing of the cars. This wear may be reduced to a considerable extent by greasing or lubricating the rails at the points of greatest wear or by greasing or spraying the wheel flanges of the locomotive or car with oil.

My invention has as an object the production of a simple, inexpensive, efficient, compact, durable and reliable mechanical lubricator adapted for attachment to the rail, and operable by the passage of a car wheel thereover, to apply lubricant to the rail at the point or points of wear.

A still further object of the invention is to provide a device which will transmit the action of the car wheel to the lubricator in such manner that the lubricant is ejected as required, but after all lubricant has been ejected, no damage will be caused to the apparatus by the continued successive contacts of wheels actuating the device.

The invention also has as an object the production of a device which will eject the lubricant in measured amounts as each wheel passes over the distributor, but will not continuously eject in case a car wheel comes to rest over the device.

Another object is the production of a device which may be easily filled and refilled with lubricant; which will show by a casual exterior inspection whether or not the lubricant is exhausted; which consists of a minimum of movable parts, thereby reducing cost of manufacture as well as renewal for wear and upkeep of the parts and which may be readily applied or removed from the rail without any reconstruction thereof or temporary removal of the rail.

Many other objects and advantages of the construction herein shown and described will be obvious to those skilled in the art from the disclosure herein given.

To this end my invention consists in the novel construction, arrangement and combination of parts herein shown and described and more particularly pointed out in the appended claims.

In the drawings, Figure 1 is a sectional view through my improved lubricator taken substan-

tially on the line 1—1 of Fig. 4, the rail being shown in section with the device applied thereto and a portion of the car wheel being shown in dotted lines;

Fig. 2 is a sectional view taken substantially on line 2—2 of Figs. 1 and 4;

Fig. 3 is a sectional view taken substantially on line 3—3 of Fig. 4;

Fig. 4 is a top elevation of the device as applied to a rail, only a portion of the rail being shown; and

Fig. 5 is an end elevation of the container and a side elevation of the rail.

In the drawings in which a preferred embodiment of the invention is shown, 1 represents the head or tread of a rail and 2 a portion of a wheel having the usual flange 3 which is customarily disposed at the inner face of the rail head. My device is adapted to be attached to the rail and is operable to deposit a particle or measured quantity of grease or lubricant at the inner side face of the rail head where it may be picked up by the flange and spread. As shown, there is provided a rail plate 6 which is of a size to fit between the underside of the rail head and the base of the rail, the same being so mounted that the face 6' is in alignment and is substantially a continuation of the innerside of the rail head. Rail plate 6 may be secured in place in any suitable manner and as shown, by means of bolts 7, the heads of which are flush with the plate 6 and which extend through the web 4 of the rail. Filler plates 8 and 9 are preferably arranged as shown, 8 serving as a seat for the plate 6 and 9 as a seat for the nut 10 which is arranged on each bolt and affords a means for drawing the parts tightly together and locking them in operative position.

Carried by the plate 6 is a lubricant container designated generally by the reference character 11 which is provided with communicating primary and secondary lubricant containing chambers 12 and 13. The container illustrated consists of a tubular shell member 14 mounted on a head 15 which is constructed to provide the secondary or compression chamber 13. The head is provided with ports 16 and 17 and with a discharge port 18. These ports are controlled by a combined valve and distributor 25 hereinafter described in detail. The head is provided with a face plate 19 arranged for attachment to the rail plate 6 by means of bolts 20 or equivalent means for the purpose. The plate 19 is preferably more or less yieldingly secured in place by means of the bolts 20, nuts 21 and springs 22. The plate

or head 19 is also recessed to provide a space 26 for the reception of the valve 25, the valve being movable vertically over the face of the rail plate 6 to apply and to distribute the lubricant and is maintained in close contact with rail plate 6 by the springs 22 previously referred to.

As shown, plate 25 is substantially a combined valve and distributor for the lubricant. It is provided with ports 27 and 28 which cooperate with the ports 16, 17 and 18 as will be hereafter described. The same is also provided with the duct or groove 29, the lower end of which communicates with the port 28 and the upper end of which terminates at the top adjacent the inner face of the rail head 1, the plate being of sufficient size to overlap the rail head as most clearly shown in Figs. 1 and 2. The plate is normally maintained in its upward position and limited in its travel by springs 31 and stop members 30. As shown, the members 30 are secured on the plate and project into a chamber 32 formed in the parts 19' of the plate 19.

When a car wheel passes over the plate, the flange 3 engages the top edge of the carrier plate or valve 25 and forces it down substantially as shown in dotted lines in Fig. 1 and after the wheel has passed, springs 21 retrieve the same to the position shown in Fig. 1. In the construction designed as shown, the flange tends to clutch or frictionally engage the plate 25 to carry it down rather than a direct positive engagement. In the preferred construction, the upper edge of the valve 25 is rounded as indicated at 33, the top edge constituting substantially a cam face which engages with flange 3 of the wheel.

The container 11 shown is provided with a closure or head 34 at the opposite end of the shell 14 and a plunger 35 is arranged within the container, this being provided with a cup-shaped washer 36 of leather or equivalent material which will be tight and prevent leakage past the plunger. A spring 37 tends to normally force the plunger toward the rail so as to expel lubricant through the port 16, port 27 and port 17 from the primary or storage chamber 12 into the secondary or compression chamber 13, when the valve 25 is depressed by the car wheel. A threaded plunger stem 36' is slidably mounted in the closure 34 and is provided with a retrieving nut 38 threaded thereon and constructed in the form of a hand wheel for convenience in operation.

The operation of the device may be briefly described as follows assuming that the container is mounted on a track rail substantially as shown at a desired point, it being understood that there may be any desired number of devices arranged at intervals along the curve. It may also be assumed that the primary and secondary chambers 12 and 13 are full of lubricant such as a grease of the desired consistency. The nut 38 is at the outer end of the stem 36'. It will be noted that in the positions shown in Fig. 1, ports 18 and 28 are in registry and it may be assumed that the groove 29 is full of grease while the port 16 is closed by the valve. As a wheel rolls over the rail and comes into engagement with the plate 25, depressing it, plate 25 is moved downwardly, closing port 18 from the secondary or compression chamber and placing ports 16 and 17 in communication through the port opening 27. The spring pressed plunger 35 forces lubricant through the port 16 from the primary or storage chamber into the secondary or compression chamber 13 compressing or putting lubricant in 13 under pressure. As soon as the wheel has

passed, however, the plate is free to move upwardly under the action of the springs 31, closing ports 16 and 17 from communication and bringing opening 28 into registry with port 18, thereby bringing the secondary chamber and the groove 29 into communication. The lubricant under pressure or compression in 13 expands through 18 and 28 and forces the lubricant in 29 outwardly or extrudes it. The next wheel depressing 25 continues the feeding of lubricant to the rail as described. It will be noted, however, that should a car stop with a wheel over the plate 25 and maintain it depressed, that while ports 16 and 17 may be in communication and there be pressure in 13, port 18 will be closed so that there will be no continued feeding of the compressed lubricant in 13 or the passageway 29 from the device. In other words, the feeding is only periodically or successively in measured quantities and not continuously. When the plunger 35 has reached the limit of its travel, the nut 38 will indicate that the container is empty and obviously this may be noted by a trackman without taking the device apart. To replenish the supply of lubricant, the nut 38 is turned down as indicated in the dotted lines in Fig. 1 compressing the spring 37 and bringing the plunger back toward the head 34. The head 34 may be removed and the lubricant in 12 be replenished, after which head 34 is replaced and the nut 38 retrieved to the position shown in full lines in Fig. 1.

It will be noted that the device consists of a minimum of parts so that there is but slight opportunity of wear or for the parts to get out of order or adjustment. Enough lubricant is fed around the plate 25 so as to lubricate the same where it engages 6 and 19. If there is any slight wear, it will be compensated for by the springs 22, the parts always being maintained in operative relation with the rail head 1.

Having thus described the invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a rail lubricating device of the kind described and in combination, a lubricant carrier plate mounted adjacent the rail in the path of a wheel flange and vertically depressible at the edge face of the rail head by a wheel flange travelling over the plate, said plate provided with a lubricant passage-way adjacent said rail face, and means mounted on said rail at said plate for depositing a lubricant in said passage-way at each upward movement of the plate.

2. In a rail lubricating device of the kind described and in combination, a lubricant carrier plate mounted adjacent the rail in the path of a wheel flange and vertically depressible at the edge face of the rail head by a wheel flange travelling over the plate, means for normally maintaining said plate in its elevated position, said plate provided with a lubricant passage-way terminating at its top edge adjacent said rail face, and pressure means adjustably mounted on the rail at said plate for depositing a lubricant in said passage-way at each upward movement of the plate.

3. In a rail lubricating device of the kind described and in combination, a face plate con-

structed to substantially fit a rail between the head and base, a wheel actuated lubricant carrier plate slidably mounted on said face plate and having a passage-way on the side adjacent the

- 5 face plate and said rail head side face, a lubricant container mounted on said face plate and arranged to maintain said carrier plate in operative relation to the rail head, said container provided with a primary lubricating chamber and 80
10 a secondary lubricating chamber, said container chambers provided with ports, and said lubricant carrier constructed with ports arranged to register with said ports upon predetermined movement upward or downward of said carrier to 85
15 connect the secondary chamber and plate passageway or the two chambers, respectively, and means for causing a pressure on the lubricant in the chambers. 90

4. In a rail lubricating device of the kind described and in combination, a face plate constructed to substantially fit a rail between the head and base and having securing means, a wheel flange actuated lubricant carrier plate slidably mounted on said face plate and having 95
20 a passage-way on the side adjacent the face plate and said rail head side face, a lubricant container adjustably mounted on said face plate and arranged to maintain said carrier plate in operative relation to the rail head, means for normally maintaining said carrier plate in elevated 100
25 position, said container provided with a primary lubricating chamber and a secondary lubricating chamber, said container chambers provided with ports, and said lubricant carrier constructed with 105
30 ports arranged to register with said container chamber ports upon predetermined upward or downward movement of said carrier, whereby lubricant under pressure is forced from the primary chamber to the secondary chamber, and thence to the rail head. 110

5. In a rail lubricating device of the kind described and in combination, a rail plate constructed to fit the rail between the head and flange thereof, a filler interposed between the rail plate and rail web, and means for securing said rail plate and filler to the rail, a container provided with a primary lubricant chamber and with a secondary lubricant chamber communicating therewith and having a discharge port, means for yieldably securing said container to said rail plate, a valve interposed between the container and rail plate and having ports formed therein constituting passages for lubricant from the primary to the secondary chamber and from the secondary chamber to the rail, and means for feeding lubricant from the primary to the secondary chamber when said valve is in the position to provide communication between the two chambers, said valve having a closure portion adapted 115
45 to cover the discharge port of said secondary chamber to prevent the discharge of lubricant from the secondary chamber to the rail when the secondary chamber is in communication with the primary chamber. 120

6. In a device of the kind described and in combination, a lubricant container having a storage chamber and a compression chamber formed therein, means for operatively securing said container to a track rail, spring actuated means for applying pressure to the lubricant in said container storage chamber, and means for controlling the discharge of lubricant from said storage chamber into the compression chamber and from the compression chamber and distributing the same on said rail. 125
130
135
140
145
150

7. In a device of the kind described and in combination, a lubricant container provided with a storage chamber and a compression chamber and means for operatively securing said container to a track rail, means for forcing the lubricant under pressure into the compression chamber from the storage chamber in said container, and means actuatable by a flanged wheel passing on the rail for controlling the discharge of lubricant from said compression chamber in measured quantities and distributing the same on said rail, said last mentioned means being positioned with respect to said compression chamber to prevent discharge of lubricant therefrom when the flanged wheel is in engagement with said last mentioned means. 90

8. In a rail lubricating device of the kind described and in combination, a face plate constructed to substantially fit a rail between the head and base, a lubricant carrier plate slidably mounted on said face plate and having a passage-way on the side adjacent the face plate and said rail head side face, said carrier operatively arranged on the face plate to frictionally engage a wheel flange, a lubricant container mounted on said face plate and arranged to maintain said carrier plate in operative relation to the rail head, said container provided with a supply lubricant chamber and a compression lubricant chamber, said container chambers provided with ports, and said lubricant carrier constructed with ports arranged to register with said ports upon predetermined movement upward or downward of said carrier to connect the compression chamber and plate passageway or the two chambers respectively, and means for causing a pressure on the lubricant in the supply chamber. 100

9. In a device of the kind described and in combination, a lubricant container having a supply chamber and a compression chamber, means for operatively securing said container to a track rail, means for applying pressure to the lubricant in said supply chamber, and a valve plate actuated by a flanged wheel passing on the rail, said plate having ports formed therein for establishing communication between said chambers when the plate is depressed by the wheel and for discharging lubricant from said pressure chamber in measured quantities and distributing the same on said rail when the wheel is disengaged from said plate. 110

10. In a rail lubricating device of the kind described and in combination, a lubricant container having a supply chamber and a compression chamber formed therein, means for securing said container to a rail, carrier means having a passageway and ports formed therein for conducting lubricant from the container and distributing the same on the rail, said carrier means being operative to position said ports for alternately establishing communication between said chambers and between said compression chamber and said passageway for controlling the discharge of lubricant in measured quantities from the container to the rail, and means for causing above atmospheric pressure on the lubricant in said supply chamber. 120

11. In a rail lubricating device of the kind described and in combination, a lubricant carrier plate mounted adjacent the rail in the path of a wheel flange and vertically movable along the edge face of the rail head, said plate being operable by the frictional engagement of the rail side of the wheel flange moving along the edge face of said rail head and provided with a lubri- 130
135
140
145
150

cant passageway adjacent said face, and means for depositing a lubricant in said passageway at each movement of the plate in one direction.

12. In a rail lubricating device of the kind described and in combination, a relatively thin vertically disposed lubricant carrier plate mounted adjacent the rail head in the path of a wheel flange and vertically depressible by frictional engagement of the rail side of the wheel flange moving along the edge face of said rail head, said plate provided with a lubricant passageway adjacent said edge face, and means operatively related to said plate for depositing a lubricant in said passageway at each movement of the plate in one direction.

13. In a rail lubricating device of the kind described and in combination, a lubricant carrier plate mounted adjacent the rail in the path of a wheel flange and vertically movable along the edge face of the rail head, said plate being operable by the frictional engagement, in a substantially horizontal and downwardly direction of the rail side of the wheel flange moving along the edge face of said rail head and provided with a lubricant passageway adjacent said face, and means for depositing a lubricant in said passageway at each movement of the plate in one direction.

14. In a rail lubricating device of the kind described and in combination, a relatively thin vertically disposed lubricant carrier plate mount-

ed adjacent the rail head in the path of a wheel flange and vertically depressible by frictional engagement in a substantially horizontal and downwardly direction of the rail side of the wheel flange moving along the edge face of said rail head, said plate provided with a lubricant passageway adjacent said edge face, and means operatively related to said plate for depositing a lubricant in said passageway at each movement of the plate in one direction.

15. In a rail lubricating device of the kind described and in combination, a container adapted to be secured to a rail and provided with a primary lubricant chamber and with a secondary lubricant chamber communicating with said primary chamber, said secondary chamber having a discharge port associated therewith, a valve interposed between the container and rail and having a plurality of ports constituting passages for lubricant from the primary to the secondary chamber and from the secondary chamber to the rail, and means for feeding lubricant from the primary to the secondary chamber when said valve is in position to provide communication between said chambers, said valve having a closure portion adapted to cover the discharge port of said secondary chamber to prevent the discharge of lubricant therefrom when the secondary chamber is in communication with the primary chamber.
